DRAPERY HOOK INSERTER

Bruno A. Lambert, Honolulu, Territory of Hawaii, assignor to George F. McMurray, Glendale, Calif.

Application September 26, 1955, Serial No. 536,652

4 Claims. (Cl. 1-47)

This invention relates to a tool adapted to facilitate the insertion of a pin-like member into fabric or the like, and is more particularly concerned with a hand tool adapted to cooperatively engage a drapery pin and make possible easy and quick insertion of the pin into a drape or the like.

Draperies are formed of materials that are quite heavy and are generally hemmed and gathered or pleated at or along their top edges to establish headings, which headings are adapted to establish what is, in effect, a relatively stiff body portion from which the remaining portion of the draperies hang.

As a result of the weight and bulk of the material forming the headings of a drapery and as a result of the necessary size and weight of the drapery pins adapted to be engaged in and to support the draperies, considerable effort is required to insert or engage the drapery pins into the headings of the draperies.

Heretofore, persons, generally women, employed in the manufacturing of draperies have been required to grasp the drapery pins between their fingers and to urge them into engagement with the draperies. Due to the effort required to engage the pins in the draperies, and due to the limited purchase a person can gain with their fingers on such pins, the task of applying such pins to the draperies has been extremely slow and oftentimes painful to the person or persons confronted with the task.

The general object of the present invention is to provide a hand tool adapted to engage and carry a drapery pin for fast, easy insertion into or with a drapery.

Another object of the invention is to provide a tool of the character referred to which will readily receive and release a drapery pin.

Still another object of the present invention is to provide a tool of the general character referred to having a head adapted to be slidably engage in the mounting hook of a drapery pin and having an elongate handle which is angularly related with the head so that it does not interfere with the work.

Another object of the present invention is to provide a tool of the general character referred to which is both easy and economical of manufacture and which requires no special skill to use.

The various objects and features of my invention will be fully understood from the following detailed description of a typical preferred form and application of the invention, throughout which description reference is made to the accompanying drawings, in which:

Fig. 1 is a side elevational view of the drapery pin tool provided by the present invention and showing a drapery pin engaged therewith and engaged in a drapery, the drapery being shown in cross section. Fig. 2 is an elevational plan view of the tool that I provide and showing a drapery pin engaged therewith. Fig. 3 is a side elevational view of the tool that I provide and of a drapery pin, the head portion of the tool being shown in section and the pin being shown in position to be engaged with

2

the tool. Fig. 4 is a view similar to Fig. 3 and showing a drapery pin of slightly different configuration, and a tool as provided by the present invention and shaped to accommodate the pin.

5 The tool provided by the present invention is adapted to releasably engage and carry a drapery pin for insertion of the pin with a drapery or the like.

The ordinary or conventional drapery pin such as is shown in Figs. 1 to 3 of the drawings, is formed of a single length of wire stock and includes generally an elongate pin portion A adapted to be inserted into a drapery, and a mounting hook portion B adapted to be engaged with some suitable support for carrying the drapery in which the pin is engaged. The pin portion A of the drapery pin is provided with a straight shank 10 having front and rear ends, a sharp point 11 at its front end and a recurved hook-like stop 12 at its other or rear end and adapted to limit engagement of the pin into the fabric of the drapery in which it is engaged.

10 20 The mounting hook B of the drapery pin is a rearwardly opening U-shaped part projecting laterally from the shank 10 of the drapery pin and having an inner leg 13 continuing forwardly from the recurved stop 12 of the pin, an outer leg 14 extending substantially parallel with the inner leg, and a substantially rounded intermediate or bottom portion 15 extending between and joining the forward ends of the legs.

25 In practice, the inner leg 13 of the mounting hook B occurs adjacent one side of the pin shank 10 and cooperates therewith to yieldingly hold or grip the drapery fabric engaged therebetween.

30 The inner and outer legs 13 and 14 of the mounting hook B of the ordinary drapery pin are generally rearwardly convergent, with the result that the open end of the mounting hook is choked down, that is, the rearmost portion of the legs are closer together than the forward portions thereof. As a result of the above, the possibility of the hook becoming disengaged from the drapery supporting means with which it is engaged, is materially reduced.

35 40 In practice, the general proportions of the mounting hooks of drapery pins are substantially the same, that is, the length and width is approximately the same or standard. The reason for the above, is so that any particular make of drapery pin can be cooperatively related to or with any one of the various makes, brands or kinds of drapery supporting means that are on the market or available, and which to a great extent have been standardized.

45 50 In practice, the differences in the shapes of various drapery pins is brought about for the most part, by the differences in the size or gauge of the wire stock from which they are made. For example, when drapery pins are formed of light weight or small gauge wire stock, the mounting hooks thereof are substantially rounded, in the manner of the pin shown in Fig. 4 of the drawings. On the other hand, when heavier gauged wire stock is employed to make drapery pins, the mounting hooks thereof are generally more angular, such as is shown in Figs. 1 to 3 of the drawings.

55 60 The tool provided by the present invention, which is adapted to facilitate insertion of drapery pins into draperies or the like, is an extremely simple unitary structure formed as by casting or the like, and includes generally, an elongate body C having front and rear ends and establishing a suitable handle, and a head D at the front end of the body and engageable in or with the mounting hook of a drapery pin.

65 70 The head D is an elongate member integrally joined to the body or handle C, and is characterized by a central portion 20 extending longitudinally thereof and corre-

sponding in general configuration with the interior of the mounting hook of an ordinary or standard drapery pin, and side portions 21 at each side of the central portion and having their peripheries projecting beyond the edges of the central portion and establishing stop shoulders 23 at each side of the central portion.

With the above relationship of parts, it will be apparent that by engaging the central portion 20 of the head D into the mounting hook B of a drapery pin, from the open end thereof, the pin is suitably supported by the tool and is yieldingly held engaged thereon by the relationship of the rearwardly convergent legs 13 and 14 of the mounting hook portion on the tool head D. It will also be apparent that the shoulders 23 on the head D, and occurring at each side of the central portion 20 thereof, serve to maintain the drapery pin in alignment with the tool and also prevent lateral shifting or displacement of the pin from the head of the tool.

In practice, after a drapery pin has been engaged on the head of the tool in the manner illustrated in Figs. 1 and 2 of the drawings, the point 11 of the pin portion A of the drapery pin can be engaged with a drapery or the like, whereupon the tool is urged forwardly in the direction indicated by the arrow X in Fig. 1 of the drawings, and the drapery pin is driven or urged into desired engagement with the drapery.

After the drapery pin is engaged in a drapery in the manner set forth above, the tool can be easily withdrawn from engagement with the drapery pin, there being sufficient frictional drag between the pin portion A of the hook and the fabric of the drapery, and sufficient gripping action by the drapery pin on the fabric occurring between the inner leg 13 of the hook B and the pin shank 10, to prevent withdrawal of the pin from the drapery by the tool.

In practice, the angle of penetration of a drapery pin into a drapery can, by employing the tool of the present invention, be advantageously controlled. In the form of the invention illustrated, I have shown the handle C of the tool as being upwardly inclined as it projects rearwardly from the head D and so that the hand of the operator gripping the tool handle will occur above and clear of the drapery being worked upon, when it is desired to insert the pin in the manner shown in Fig. 1 of the drawings.

In Figs. 1 to 3 of the drawings, I have illustrated the head of my tool as being formed so that it can be advantageously engaged in the mounting hooks of most standard drapery pins, to hold the pins for insertion into a drapery in the desired manner. It is to be understood, however, that, in practice, the head of the tool could be formed to correspond exactly with one particular mounting hook configuration of a given make or size of drapery pin. In Fig. 4 of the drawings, I have shown the tool head D' as being the exact or same shape as the mounting hook B' of the drapery pin.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A tool adapted to releasably engage and carry a drapery pin having an elongate shank with a pointed front end and a laterally projecting rearwardly opening mounting hook including, an elongate handle, a head project-

ing forwardly from the handle and having a central portion of substantially the same configuration as the mounting hook and engageable in the inside of the mounting hook on the drapery pin from the rearwardly opening end thereof and side portions at the sides of the central portion and projecting therefrom to establish shoulders engageable with the sides of the mounting hook.

2. A tool adapted to releasably engage and carry a drapery pin having an elongate shank with a pointed front and a laterally projecting rearwardly opening mounting hook with inner and outer legs adjacent the rear end including, an elongate handle, a head projecting forwardly from the handle and being of substantially the same configuration as the interior of the mounting hook and engageable on the hook from the open rear end thereof, the rear end portion of the legs of the mounting hook converging to restrict the opening therebetween and yieldingly passing the head of the inserter when the hook and the head are engaged and disengaged and normally yieldingly gripping the head when the head is freely engaged in the hook.

3. A tool adapted to releasably engage and carry a drapery pin having an elongate shank with a pointer front and a laterally projecting rearwardly opening mounting hook with inner and outer legs adjacent the rear end including, an elongate handle, a head projecting forwardly from the handle and being of substantially the same configuration as the interior of the mounting hook and engageable in the hook from the open rear end thereof, side portions at the sides of the central portion and projecting therefrom to establish shoulders to occur adjacent the opposite sides of the mounting hook engaged on the central portion and preventing lateral displacement of the hook from the head, the rear end portions of the legs of the mounting hook converging to restrict the opening therebetween and yieldingly passing the head of the inserter when the hook and the head are engaged and disengaged and normally yieldingly gripping the head when the head is fully engaged in the hook.

4. A tool adapted to releasably engage and carry a drapery pin having an elongate shank with a pointer front and a laterally projecting rearwardly opening mounting hook with inner and outer legs adjacent the rear end including, an elongate handle, a head projecting forwardly from the handle and being of substantially the same configuration as the interior of the mounting hook and engageable in the hook from the open rear end thereof, side portions at the sides of the central portion and projecting therefrom to establish shoulders to occur adjacent the opposite sides of the mounting hook engaged on the central portion and prevent lateral displacement of the hook from the head, the rear end portions of the legs of the mounting hook converging to restrict the opening therebetween and yieldingly passing the head of the inserter when the hook and the head are engaged and disengaged and normally yieldingly gripping the head when the head is fully engaged in the hook, the handle projecting rearwardly and upwardly relative to the longitudinal axis of the pin.
